UNITED STATES PATENT OFFICE

JAMES J. PARKER, OF ABSECON, NEW JERSEY

TAPPET VALVE

Application filed April 19, 1930. Serial No. 445,633.

The present invention relates to tappet valves, and is particularly concerned with valves for internal combustion engines.

One of the principal disadvantages of the tappet valves of the prior art lies in the fact that the prior valves have been more noisy than other types of valves on account of the clearance required between the end of the valve stem and the actuating mechanism thereby causing a tap or click when the valves are first engaged by the cam, rocker arm or other mechanism in the opening of a valve. Tappet valves are capable of more effective closure than other types of valves when used with proper clearance, and clearance is usually necessary on account of the expansion of the parts of the engine when the engine is heated. If such clearance were not provided, the complete closure of the tappet valve would not be assured under all conditions, with a consequent loss of power, and the inherent advantages of the tappet valve would not be fully utilized.

One of the objects of the present invention is the provision of an improved tappet valve arrangement whereby all of the tapping noise of the valves is eliminated.

Another object is the provision of an improved tappet valve actuating mechanism which is peculiarly adapted to accomplish a more silent operation of the valves.

Another object of the invention is the provision of an improved valve arrangement in which the slight noise incident to the operation of the valve is made inside the intake or exhaust manifolds or inside the engine block, where it is muffled and dissipated thereby substantially reducing the noise of the engine.

Another object is the provision of a device of the class described whereby the accomplishment of adjustments is made extremely simple, eliminating the necessity for use of a thickness gauge, and assuring the use of the particular clearance recommended and provided by the factory for each valve, at all subsequent adjustments, such as after grinding, etc.

Another object of the invention is the provision of an improved tappet valve arrange-

ment whereby the clearance for the valves may be automatically predetermined, thereby enabling the adjustment of valve clearance by unskilled labor with greater accuracy, with less difficulty, and assuring proper clearance for each individual valve at all times.

Another object is the provision of an improved tappet valve construction by means of which a closer valve fit may be accomplished through the provision of a valve which is adapted to seat in the same position at all times.

Another object is the provision of an improved valve of the class described, which is simple in its construction, efficient in its operation, durable, and capable of economical manufacture and assembly.

Another object is the provision of an improved tappet valve of the class described which is adapted to be installed in existing internal combustion engines for replacement or repair of the existing valves, to embody the present improvements in such engines without excessive labor.

Other objects and advantages of the invention will be apparent from the following description and from the accompanying drawings, in which similar characters of reference indicate similar parts throughout the several views.

It should be understood that while all of the foregoing features cooperate to accomplish the best results, the more simple forms of the invention need not necessarily include all of the advantageous features described herein, and the present invention includes all of the combinations and permutations or modifications of the present embodiments which have any or all of the features disclosed herein.

Referring to the drawings, of which there are three sheets,

Fig. 1 is a sectional view taken on the plane of the axis of a valve stem showing an exemplary form of installation employing the present tappet valve;

Fig. 2 is a similar view in partial section of a tappet valve assembly of a simplified form;

Fig. 3 is a fragmentary sectional view of another modification;

Fig. 4 is an enlarged sectional view taken on the plane of the line 4—4 of Fig. 1;

Fig. 5 is a sectional view similar to Fig. 1 of a modified form of construction;

Fig. 6 is a transverse sectional view taken on the plane of the line 6—6 of Fig. 5;

Fig. 7 is a side elevational view of the device shown in Fig. 5 with the valve chamber in section;

Fig. 8 is a fragmentary longitudinal sectional view taken on the axis of a valve stem illustrating the valve clearance adjustment which may be utilized in any of the valves described herein;

Fig. 9 is a sectional view taken on the plane of the line 9—9 of Fig. 8;

Fig. 10 is a sectional view taken on the plane of the line 10—10 of Fig. 8;

Fig. 11 is a view similar to Fig. 2 of a modified form of tappet valve;

Fig. 12 is an elevational view of the lower end of the valve assembly of Fig. 1 with the main valve spring and washer removed;

Fig. 13 is an enlarged view of the clearance adjustment feature with the clearance adjuster in normal position; and

Fig. 14 is a similar view with the clearance adjuster in position to facilitate the automatic adjustment of a valve to the predetermined clearance provided by the factory.

Referring to the first sheet of drawings, Fig. 1 is an exemplary installation of a tappet valve constructed according to the present invention. The installation is embodied in an internal combustion engine having an engine block 20 which is formed with a valve opening having a valve seat 21 adapted to be engaged by the complementary seating surface 22 on a valve disc 23. The engine block 20 is customarily provided with a valve guide 24 for the valve stem 25, for movably supporting the tappet valve with respect to the engine block 20 and valve seat 21, and the valves may be actuated by any type of actuating mechanism 26, such as the usual rocker arm which is provided with an adjustable screw bolt 27 having a lock nut 28 for securing the bolt 27 in the desired adjusted position.

The valves of the prior art have customarily been provided with a clearance between the actuating mechanism 26 and the end of the valve stem 25, and the major part of the noise which is caused by the tappet valves of the prior art is occasioned by the click or tap between the valve actuating mechanism and the valve stems at the bolt 27.

The present tappet valves are preferably provided with an auxiliary actuating member 29 which extends from a point outside the internal combustion chamber into the intake or exhaust manifold or valve chamber 30 for the purpose of engaging a valve part and actuating the valve to open position. The

present arrangement is, of course equally adaptable to engines with overhead valves or other types. The valve actuating member 29 may be in the form of a sleeve as shown in Figs. 1 and 2, slidably mounted on the valve stem 25 and also mounted for sliding movement within the valve guide 24, and the sleeve 29 is adapted to engage the valve 23 at some point within the valve chamber 30.

The clearance which is necessary and desirable to assure the complete closure of the valves under all conditions may thus be provided between the shoulder 31 on the tappet valve and the end 32 of the valve actuating member 29, and the sleeve 29 is also preferably provided with a resilient member such as a coil spring 33 located within the sleeve between the end of valve stem 25 and the closed end 34 of sleeve 29. The spring 33 urges the sleeve 29 downward upon the valve stem 25 in Fig. 1 and tends to maintain the clearance between the parts 31, 32 in order to secure the valve stem and valve actuating member 29 in predetermined relation. The valve stem 25 is preferably formed with a transverse aperture 35 through which is adapted to pass a pin or key 36 also preferably formed with a slot 37. The sleeve 29 is also formed with registering apertures 38 having sufficient clearance with respect to the key 36 so that the key does not engage either the lower nor the upper edges of the slots 38 but the engagement between the sleeve and valve always takes place at the shoulders 31, 32 located in the valve chamber. In other words, a greater clearance is provided between the points 39, 40 than between the points 31, 32.

The slot 37 is of sufficient width to receive valve stem 25 and aperture 35 is of sufficient size to pass key 36 so that after the key is located in the position of Fig. 1 or Fig. 2, the spring 33 urges the lower wall of aperture 35 into engagement with key 36 and the upper side of key 36 into engagement with the upper walls of apertures 38 in sleeve 29, before the valve is installed. After the valve is installed, however the key 36 should preferably have a clearance with respect to the bottoms and tops of slots 38 to prevent any tap at these points. The relation of parts after installation is shown in Figures 1 and 2.

All of the features so far described may be embodied in the very simple type of tappet valve disclosed in Fig. 2, which is preferably provided with a sleeve 29 of such size that the sleeve 29 will fit in the valve guide of the internal combustion engine in which the present valves are to be placed.

The valve stem 25, may either be made smaller than the standard valve stem for that engine by twice the thickness of the wall of sleeve 29, provided the stem is still strong enough or a larger stem and sleeve can be used by merely enlarging the valve guide. It will thus be evident that the present tappet

valves may be installed in ordinary existing internal combustion engines without materially changing the structure of the engine.

The key 36 is also adapted to provide a support for a spring washer 41, which surrounds the sleeve 29 and valve stem 25 and the valve may be urged into closed position by a spring 42 having one end seated about the downwardly projecting part 43 of valve guide 24 and the other end seated upon the washer 41.

The spring 42 reacts against engine block 20 and urges washer 41 and key 36 downward in Fig. 1. Key 36 engages valve stem at slot 37 and it will thus be evident that the spring 42 urges the valve disc 23 into closed or seated position.

The valve actuating member 29 is preferably provided with a plurality of apertures 44 for receiving a small amount of lubricant and the embodiment shown in Fig. 1 is also peculiarly adapted to effect the seating of the valve disc 23 in exactly the same position at all times. For this purpose the valve guide 43 may be provided with inwardly projecting teeth or keys 45 adapted to slidably engage in the longitudinally extending grooves 46 formed in the valve actuating member 29. The keys 45 prevent rotation of the tappet tube 29 in valve guide 43 but permit the desired sliding movement and the key 36 prevents relative rotation between tappet tube 29 and valve stem 25, but also permits the necessary relative sliding movement between these parts.

The valve disc 23 is thus positively prevented from rotating with respect to the valve seat 21 and every part of the seating surface 22 on the valve disc will always engage the same part of the valve seat 21, thereby assuring a more perfect closure than can be accomplished by the freely rotating valves of the prior art. The slots 46 are preferably extended to the extreme end of tappet tube 29 so as to facilitate the assembly of the parts by sliding tappet tube 29 into valve guide 24 from one end.

The present tappet valves may also be provided with an arrangement for simplifying valve adjustments, eliminating the necessity for using a thickness gauge and assuring the particular clearance recommended and provided by the factory for the valve. The valve clearance adjuster may consist of a movable head or adjuster 47 carried by the end of tappet tube 29 or interposed between the valve actuating mechanism 26 and the valve at any convenient point.

In the present embodiment the adjuster 47 consists of a relatively short metal member of a shape similar to that of a tappet tube 29 and provided with a centrally located rivet 48 fixedly secured in head 47 but slidably mounted in an aperture 49 formed in the end 34 of tappet tube 29. The end 34 of tap-

pet tube 29 is provided with a groove 50 and the adjacent side of adjuster 47 is provided with a ridge 51 capable of being received in the groove 50. The depth of groove 50 is relatively immaterial but the height of ridge 70 51 is equal to the amount of clearance required for the particular valve upon which the adjuster is located, and the rivet 48 is of sufficient length to permit the adjusting head 47 to be moved away from the end of tappet tube 29 and rotated so that the ridge 51 is moved out of groove 50 into engagement with the relatively flat end 52 of tappet tube 29. The rotation of the adjuster 47 thus increases the length of the tappet tube 29 by an amount 75 which is exactly equal to the clearance desired for the tappet of the particular valve and the intake and exhaust valves of combustion engines may thus be provided with adjusters having the predetermined clearance 80 85 adjustment recommended for that particular engine.

The present tappet valves are intended to be used with the head 47 in direct engagement with the bolt 27 or other valve actuating mechanism at all times, the appropriate valve clearance being provided at the points 31, 32 in the valve chamber. The present tappet valves may be used with all types of internal combustion engines and the term 95 valve chamber is used to include those parts of the internal combustion engine, such as combustion chamber, intake manifold or exhaust manifold in which the valves may be located.

Referring to Fig. 3, this is a fragmentary view of a modification in which the tappet tube 29 is provided with an outwardly flaring part 53 adapted to engage the lower side 54 of valve disc 23.

Referring to Fig. 11, this is a similar view of a modified form of tappet valve in which the valve stem 25 is tubular in form, being formed with an axial bore 55a for receiving a tappet rod 56a adapted to perform the same function as the tappet tube 29 of Figure 1.

In this embodiment the auxiliary spring 33 has been omitted, the tappet rod 56a is returned by gravity and the tappet rod 56a 115 is adapted to actuate valve disc 23 to the open position through the engagement of the end 57a of the tappet rod with the end 58a of bore 55a. If desired a spring may be placed between the end of the valve stem 25 and the end of rod 56a. The bore 55a is preferably provided with a plurality of apertures 59a communicating with the valve chamber 30 so that the tap of the tappet rod 56a against the valve takes place within the valve chamber, the points 57a and 58a of Fig. 11 corresponding to the points 31 and 32 of Fig. 1.

Figs. 12, 13 and 14 are fragmentary elevational views of the lower end of tappet valve of Fig. 1. Fig. 13 illustrates the valve ad-

juster 47 in the normal position with the clearance ridge 51 in the groove 50, while Fig. 14 shows the clearance adjuster 47 in the position which it assumes during the adjustment of the valve clearance.

The valve clearance may be adjusted as follows: The lock nut 28 is first loosened and the bolt 27 screwed away from adjusting head 47, after which the adjuster 47 may be rotated to the position of Fig. 14. The bolt 27 on the rocker arm or other actuating mechanism is then screwed out until the bolt engages adjuster 47 moving tappet tube 29 upward into engagement with the valve at the point 31, and this point of adjustment is felt by the operator by the increased resistance to the adjustment of the screw 27 which takes place as soon as the clearance 31, 32 is taken up and the screw 27 commences to lift the valve off its seat.

The bolt 27 may thus be adjusted so that there is no clearance between the valve mechanism with the adjuster in the position of Fig. 14, after which the lock nut 28 is set and the adjuster 47 moved from the position of Fig. 14 to that of Fig. 13. The spring 33 then retains the tappet tube in engagement with the adjuster 47 maintaining a clearance at the point 31, 32, which clearance should be equal to the height of the ridge 51 and the clearance may thus be predetermined by use of an appropriate adjuster on the tappet valve.

Referring to Figs. 5, 6, and 7, these are similar views of a modified form of construction having a different form of valve actuating member. In this embodiment the valve disc 23, valve stem 25 and valve seat 21 may be substantially as described with respect to Fig. 1. The valve guide 24 is preferably provided with an enlarged bore 53 capable of receiving a valve stem guide 54.

The valve stem guide 54 comprises a substantially cylindrical member formed with an axial bore 55 for slidably supporting the valve stem 25 and with a pair of oppositely disposed slots 56 for receiving the legs 57 of a valve actuating or tappet member 58.

The valve stem guide 54 may be threaded into the bore 53 or it may be a close frictional fit as shown in Fig. 6 so that the valve stem guide 54 forms a fixed part of the valve guide 24 when the parts are assembled as shown in Fig. 5. The lower end of valve stem guide 54 may be provided with a reduced portion 59, forming an annular shoulder 60 adapted to receive the washer 61, forming a seat for a helical spring 62. The end of valve stem 25 is also provided with a transverse bore 63 for receiving a key or pin 64 which supports a washer 65 forming a seat for the opposite end of spring 62.

The spring 62 reacts against washer 61 and the engine block urging the washer 65,

valve stem 25 and valve disc 23 downward into closed position.

The valve actuating member 58 of this embodiment is preferably formed with a pair of legs 57 adapted to be slidably received in the guide member 54, and provided at one end with means for engaging valve 23 within the valve chamber 30 and at the opposite end with means for engagement with a valve actuating mechanism 26. The legs 57 are thus joined by a yoke 66 at the upper end and the yoke 66 is provided with a bore 67 for receiving valve stem 25. The upper surface 68 of yoke 66 is adapted to engage a shoulder 69 on valve 23 and the clearance between shoulders 68, 69 is the usual tappet valve clearance for the particular valve in use. The lower ends of the legs 57 are also joined by a yoke 70 which may be made thicker at 71 to provide an increased area for the downwardly projecting lug 72, which is adapted to be engaged by the screw bolt 27 on a valve actuating mechanism 26 such as the ordinary rocker arm.

The legs 57 are of sufficient length so that the clearance between the end 73 of valve stem 25 and the inner surface 74 of yoke 70 is greater than the valve clearance 68, 69. The legs 57 and yokes 66, 70 thus form a framework embracing the valve stem 25 and adapted to be actuated by the valve mechanism 26 to tap some part of the valve 23 located within valve chamber 30, and thus effect the opening of the valve by the engagement of two parts having their clearance within the valve chamber, intake or exhaust manifold or combustion chamber.

The valve actuating member 58 preferably has its legs 57 formed with off-sets 75 below the guide member 24 so that the space between the legs 57 of tappet member 58, which is adapted to receive spring 62, is also of sufficient size to pass the guide member 54 and facilitate the assembly of these parts.

Referring to Figs. 8, 9, and 10, these are fragmentary views of a modified form of valve clearance adjustment mechanism which may be employed in any of the forms of tappet valves described herein. In this embodiment the rivet 48 is also fixedly supported upon the valve adjuster 47 and slidably mounted in a bore in the end 34 of the tappet member 29.

The valve adjuster is also provided with the ridge 51 capable of being received in groove 50 but the inner end of rivet 48 is riveted or otherwise secured to a spring member 76, having its outer ends 77 curved downward to engage the inner surface of the wall 34. The spring 76 urges the valve adjuster into the position of Fig. 8 and tends to maintain these parts in a proper position for normal valve operation, but due to the tapered surfaces 78 on ridge 51 and groove 50 the valve adjuster 47 may be cammed down.

ward by a rotative movement of the adjuster 47 and the valve adjustment may be accomplished in exactly the same manner as that previously described.

5 The valve adjuster 47 may also be provided with a stop pin 79 fixedly secured to the adjuster 47 and adapted to project into an arcuate slot 80 formed in the end 81 of tappet member 29. The ends of the slot 80 definitely limit the rotative movement of the valve adjuster 47 and prevent it from being moved too far in the operation of making an adjustment.

10 The operation of the present tappet valve 15 may be described as follows: All of the valves described herein are provided with a valve actuating member which extends from some point inside the valve chamber, manifold or combustion chamber, to a point 20 outside such chamber where the valve actuating member is directly engaged at all times by the valve actuating mechanism without clearance.

25 The clearance which is necessary and desirable to assure the complete closure of the tappet valves at all times, is provided between the inner end of the actuating valve member or tappet member and some part of the valve so that the tap incident to the operation of 30 the valve occurs within the combustion chamber or valve chamber where the noise is dissipated, muffled or otherwise prevented from coming to the ears of the operator.

35 The present tappet valve construction is thus adapted to eliminate all noise incident to the usual tappet valves outside of the combustion chamber and to transfer the tap, so to speak, to a point within the manifold or combustion chamber where it will not be 40 heard. Since no noise is experienced from the engagement of the valve 23 with its seat 21 it will be evident that the tap between the tappet member and the valve in the valve chamber will also be dissipated in the same manner.

45 If desired auxiliary springs may be used to hold the ordinary tappet assembly 26, 27, 28 snugly against the cam on the cam shaft.

50 The foregoing feature of silent tappet operation may also be used in connection with the feature of preventing the rotation of the valve 23 so that the valve will always seat in exactly the same position, which assures a more perfect closure than is possible where 55 the valve rotates about its stem. The rotation of the ordinary valve on its stem very often results in the lifting of the valve seating surface 22 from its seat 21 at some point and this effect is eliminated by the construction shown 60 in Fig. 1.

65 The present valves may be adjusted in the usual manner by measuring the clearance between the valve actuating member and the tappet member but the valves preferably also include the valve adjuster which is provided

with a clearance adjustment recommended for that particular valve, and the clearance adjustment may be made by simply rotating the adjuster, setting the screw bolt 27 and then returning the adjuster to the normal 70 position as previously described.

75 The present invention is thus adapted to utilize all of the inherent advantages of tappet valves while still eliminating the disadvantages such as the tappet noise, rotation of the valve, and difficulty of securing accurate adjustment. Any of the novel features or structures described herein may be combined with any of the features shown in other figures and the present embodiments are merely 80 exemplary of some of the forms of the invention.

85 While I have illustrated and described a specific embodiment of my invention, many modifications may be made without departing from the spirit of the invention, and I do not wish to be limited to the precise details set forth but desire to avail myself of all changes within the scope of the appended claims.

90 Having thus described my invention, what I claim as new and desire to secure by Letters Patent of the United States is:

1. A tappet valve comprising a valve disc, a valve stem, and a sleeve carried by said stem and slidably mounted thereon, a stop member carried by said stem and engaging said sleeve to limit the clearance between said sleeve and valve, and a spring tensioned between said stem and sleeve to maintain said clearance. 100

105 2. A tappet valve comprising a valve member formed with a seating surface, and having a valve stem, said stem being provided with an axially extending bore adapted to communicate with the interior of the manifold, a valve actuating rod slidably mounted in said bore and projecting from the end thereof, said rod being adapted to engage the end of said bore to actuate said valve and having a predetermined clearance between 110 the end of said rod and said bore, and a stop member traversing said valve stem and rod, said rod having an enlarged aperture for said latter member to permit relative movement between said rod and stem. 115

120 3. A tappet valve comprising a valve formed with a seating surface and with a valve stem, and a valve engaging member comprising an elongated tube located about said stem and having an outwardly flaring end for engaging beneath said valve, the valve clearance being provided between said outwardly flaring end and the lower surface of said valve.

125 4. A tappet valve assembly comprising a valve stem guide having an inwardly projecting lug, a tappet valve having a valve seating surface, said tappet having a stem located in said guide, a valve actuator non-rotatably mounted on said stem between said stem and 130

guide, said actuator having a longitudinally extending slot for engagement with said lug to prevent rotation of said valve.

5. In an internal combustion engine, the combination of an engine block having a valve seat with a valve guide, a valve having a valve stem, a sleeve slidably mounted on said guide and having a clearance between the end of said sleeve and said valve, and a 10 valve actuating mechanism engaging the end of said sleeve.

6. In an internal combustion engine, the combination of an engine block having a valve seat with a valve guide, a valve having a 15 valve stem, a sleeve slidably mounted on said guide and having a clearance between the end of said sleeve and said valve, and a valve actuating mechanism engaging the end of said sleeve, said sleeve and stem having 20 registering transverse apertures and a transverse member located in said apertures and adapted to prevent relative rotation between said sleeve and stem.

7. In an internal combustion engine, the 25 combination of an engine block having a valve seat with a valve guide, a valve having a valve stem, a sleeve slidably mounted on said guide and having a clearance between the end of said sleeve and said valve, a valve 30 actuating mechanism engaging the end of said sleeve, said sleeve and stem having registering transverse apertures and a transverse member located in said apertures and adapted to prevent relative rotation between 35 said sleeve and stem, said transverse member having a slot for receiving a portion of said stem, and a spring tensioned between the engine block and said transverse member to maintain said portion in said slot.

40. In witness whereof, I hereunto subscribe my name this 12 day of April, 1930.

JAMES J. PARKER.
